INVENTOR.

Conrad Jurkovich,

BY

Geo. P. Kimmel.

ATTORNEY.

UNITED STATES PATENT OFFICE

CONRAD JURKOVICH, OF JOLIET, ILLINOIS, ASSIGNOR OF ONE-HALF TO PHILIP HIBLER, OF JOLIET, ILLINOIS

SUSPENSION DEVICE

Application filed December 9, 1929. Serial No. 412,857.

This invention relates to a suspension device designed primarily for use for suspending trousers and skirts from garment hangers, but it is to be understood that a suspension device, in accordance with this invention may be employed in any connection for which it may be found applicable, and the invention has for its object to provide, in a manner as hereinafter set forth, a device for suspending a pair of trousers from a garment hanger to prevent the cross creasing of the trousers as is the case when the trousers are folded upon themselves and supported in suspending position on the hanger bar of the hanger.

A further object of the invention is to provide, in a manner as hereinafter set forth, a suspension device capable of being detachably connected with one end of a pair of trousers and with a garment hanger or other support for the purpose of suspending the trousers lengthwise, thereby overcoming cross creasing of the trousers as is now the case when the latter are suspended from a garment hanger.

Further objects of the invention are to provide, in a manner as hereinafter set forth, a suspension device for the purpose referred to which is simple in its construction and arrangement, strong, durable, compact, thoroughly efficient in its use, detachably connected in a convenient manner with respect to the garment to be suspended, and further removably connected to a suitable support therefor, and inexpensive to manufacture.

With the foregoing and other objects in view the invention consists of the novel construction, combination and arrangement of parts as hereinafter more specifically described, and illustrated in the accompanying drawing, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a fragmentary view of a pair of trousers showing the adaptation there-

with and with a garment hanger of a pair of suspension devices in accordance with this invention.

Figure 2 is a section on line 2—2, Figure 1.

Figure 3 is an elevation of the device showing the adaptation thereof for suspending a globular article.

Figure 4 is an elevation of a modified form of suspension device in accordance with this invention.

Although the suspension device is designed primarily for suspending trousers to prevent the cross creasing thereof, however it is to be understood that it can be employed for suspending any form of objects capable of being connected to either end of the device. The device is illustrated in position for suspending a pair of trousers and also a globular object.

In the drawing, 1 indicates a garment hanger in the form of a substantially, triangular shaped frame having extended from the top thereof a hook 2. The frame includes a top portion 3 which depends from the hook 2, a pair of oppositely extending side portions 4, 5 which extend at a downward inclination with respect to the top portion 3, and a bottom portion 6 which is horizontally disposed and connects the side portions 4, 5 together. The bottom portion 6 provides a suspension bar of the hanger and generally, when suspending a pair of trousers from the hanger, the trousers are folded upon themselves and extended over the bottom portion 6, and the latter supports the trousers from the bends between the folds. If the trousers are suspended for any length of time a bend or cross crease is formed at the knee portion thereof, which is objectionable, and if the crease is very marked it necessitates the pressing of the trousers again.

Referring to Figures 1, 2 and 3 of the drawings, a suspension device in accordance with this invention comprises a hook part 7 provided with an inwardly curved bill 8 and a shank 9 having an inclined portion terminating at one end into a semi-circular portion which merges into the bill 8. The other end of the inclined portion of the shank 9 terminates in a resilient coupling part 10

formed of a pair of oppositely inclined side portions 11, 12, a curved coupling portion 13 connecting outer ends of the side portions 11, 12 together and an outwardly extending, 5 inclined, lateral extension or finger portion 13 into which merges the inner end of the side portion 12. The shank 9 merges into the side portion 11. The side portions 11, 12 extend from the coupling portion 13 toward 10 each other to form, in connection with the latter a loop 15 which is open at the point of mergence of the shank 9 with the side portion 11. The loop 15 gradually increases in width from its open end 16 to the coupling 15 portion 13. The bill 8 of the hook part 7 is tapered toward its free end and the latter opposes and is arranged in spaced relation with respect to the finger or thumb portion 14. A part of the inclined portion of the shank 9, the 20 curved portion of the latter and bill 8 form a split loop of materially greater width than the loop 15. The loops open towards and are spaced from each other by the inclined portion of shank 9.

25 As illustrated in Figure 1, a pair of trousers 17 is suspended lengthwise, by a pair of suspension devices in accordance with this invention, from the side portions 4, 5 of the frame of the hanger. The hook part 7 of each suspension device is extended through the waist band 18 of the trousers 17, but the apertures formed by the hook parts 7 are very small and do not mar the appearance of the trousers when they are removed from 30 said hook parts. The holder parts 10 of the suspension devices as shown in Figure 1 are mounted upon the side portions 4, 5 of the frame of the hanger. The finger or thumb pieces 14 facilitate the positioning of the 35 suspension device upon the side portions 4, 5. As the holder parts 10 are resilient, they bind against the portions 4, 5 of the frame of the hanger.

40 Figure 3 of the drawing discloses the hanger device as suspending a globular element 19 and which is provided with an eye 45 to receive the holder part 10 of the device, and the object or article 19 is suspended from said holder part. The hook part 7 is connected to any suitable support for the purpose of suspending the device in position for the purpose of suspendingly supporting the object or article 19 from the holder parts 10.

45 The modified form shown in Figure 4 includes a hook part 21 of the same form as the hook part 7 shown in Figure 2. The device shown in Figure 4 includes a holder part 22 which is oppositely disposed with respect to a holder part 10. The shank 23 of hook 50 part 7 terminates in the side portion 24 of the holder part 22 and said side portion 24 is angularly disposed with respect to the rearwardly inclined shank 23 of the hook part 21. Opposing the side portion 24 of the part 22 55 as well as extending thereto at an inclina-

tion, is the other side portion 25 of holder part 22. The side portion 25 is arranged outwardly with respect to the shank 23 and terminates in a laterally projecting downwardly inclined finger or thumb portion 26. 70 The side portions 24, 25 are connected together by a curved coupling portion 27.

In the form shown in Figure 4, the finger or thumb portion 26 is not arranged in opposed spaced relation with respect to the bill 75 28 of hook part 21, but opposes the inclined shank 23 on the outer side of the latter. The side portions 24, 25 and coupling portion 27 form a loop 29 open at its lower end as at 30 and gradually decreasing in width from such 80 end 30 to the coupling portion 27.

The device is to be constructed of wire of the desired gauge, possessing a non-rusting characteristic and which will not bend under normal usage.

85 What I claim is:

1. A suspension device comprising a body portion formed of a hook part and a resilient holder part, said hook part comprising a shank and an inwardly directed bill, said shank formed of an inclined portion and a semi-circular portion, said inclined portion merging at one end into said semi-circular portion, said semi-circular portion terminating in said bill, a part 90 of the inclined portion of said shank, the curved portion of the shank and said bill co-acting to provide a split loop open at its inner end, and said holder part including a pair of oppositely inclined side portions and a curved 95 coupling portion between one end of said side portions, the other end of one of said side portions merging into the other end of said inclined portion of said shank, that side portion merging into said shank inclining in an opposite direction with respect to the direction of inclination of the shank, the other end of said other side portion terminating in a laterally disposed finger inclining downwardly from 100 its inner to its outer end, said side and coupling portions providing a split loop open at 110 its inner end and gradually increasing in width from its inner towards its outer end, said loops opposing each other in spaced relation and said loop provided by the shank 115 and bill being of greater width than said other loop.

2. A suspension device comprising a body portion formed of a hook part and a resilient holder part, said hook part comprising a 120 shank and an inwardly directed bill, said shank formed of an inclined portion and a semi-circular portion, said inclined portion merging at one end into said semi-circular portion, said semi-circular portion terminating in said bill, a part of the inclined portion of said shank, said curved portion of the shank and said bill co-acting to provide a split 125 loop open at its inner end, said holder part including a pair of oppositely inclined side por- 130

tions and a curved coupling portion between one end of said side portions, the other end of one of said side portions merging into the other end of said inclined portion of said shank, that side portion merging into said shank inclining in an opposite direction with respect to the direction of inclination of the shank, the other end of said other side portion terminating in a laterally disposed finger inclining downwardly from its inner to its outer end, said side and coupling portions providing a split loop open at its inner end and gradually increasing in width from its inner towards its outer end, said loops opposing each other in spaced relation and said loop provided by the shank and bill being of greater width than said other loop, and said bill having its free end disposed directly beneath and spaced from said finger.

20 In testimony whereof, I affix my signature hereto.

CONRAD JURKOVICH.
